FIG. 8

FIGURE 1 is a left side, top and front perspective view of a video tape recorder showing one form of my new design wherein both the supply and take-up reel turntables are visible.

FIGURE 2 is a right side elevational view of the top plate assembly of the video tape recorder shown in FIGURE 1.

FIGURE 3 is a left side elevational view of the top plate assembly of the video tape recorder shown in FIGURE 1.

FIGURE 4 is a front elevational view of the top plate assembly of the video tape recorder shown in FIGURE 1.

FIGURE 5 is a top or plan view of the video tape recorder shown in FIGURE 1.

FIGURE 6 is a rear elevational view of the top plate assembly of the video tape recorder shown in FIGURE 1.

FIGURE 7 is a left side, top and front perspective view of a video tape recorder showing another form of my design wherein the take-up reel turntable in the right rear corner is enclosed by a cover.

FIGURE 8 is a right hand elevational view of the top plate assembly of the video tape recorder shown in FIGURE 7.

The dominant features of my designs reside in the portions shown in solid lines.

I claim:

The ornamental design for a video tape recorder, substantially as shown and described.
